UNITED STATES PATENT OFFICE.

HOARD LEE, OF SHREVEPORT, LOUISIANA.

SELF-SERVING STORE.

1,378,417.

Specification of Letters Patent. Patented May 17, 1921.

Application filed May 11, 1920. Serial No. 380,634.

To all whom it may concern:

Be it known that I, HOARD LEE, citizen of the United States, residing at Shreveport, in the parish of Caddo and State of Louisiana, have invented certain new and useful Improvements in Self-Serving Stores, of which the following is a specification.

This invention relates to new and useful improvements in a self serving store.

10 One object of the invention is to provide a self serving store with display shelves so arranged that each customer may pass along the shelving, wherein the goods to be sold are displayed, and select such articles of 15 merchandise as he may desire which are thereafter checked at the checking counter, arranged near the exit, and there paid for.

Another object of the invention is to provide a store equipped with shelving arranged 20 in a general zigzag form so as to produce a number of isles, each isle having an entrance turn-stile and a central partition so that the customer may enter either isle desired without passing through the entire 25 zigzag course of the shelving.

With the above and other objects in view the invention has particular relation to certain novel features of construction, arrangement of parts and use, an example of which 30 is given in this specification and illustrated in the accompanying drawings, wherein:

Figure 1 shows a plan view of the store room, and

Fig. 2 shows a rear view of the shelving.

35 Referring now more particularly to the drawings, wherein like numerals of reference designate similar parts in each of the figures, the numeral 1 refers to a store room having the usual side and end walls. In 40 the front end are the entrance doors 2, 2 which lead into the vestibule 3 which is formed by means of the transverse partition 4. This partition has the inlet door 5 and the exit door 6 arranged at opposite 45 sides of the room and between them there is the checking counter 7. Through the inlet door 5 customers may enter the ante-room 8 and leading from this room rearwardly there is a row of shelving 9 which is 50 spaced from the wall forming an isle 10. The shelving 9 extends back usually about $\frac{3}{4}$ of the distance from the front to the rear wall and then across the room following a 55 general zigzag course toward the front of the room and forming the isles 11, 12 and 13 arranged parallel and opening in the

same direction along which the customers pass in selecting goods. Arranged alternately with the isles 11, 12 and 13 are the 60 isles 14, 15 and 16, which open in the same direction providing passageways for supplying the shelving with the goods to be sold from the rear. A low partition 17 extends from the ante-room 8 back parallel with the row of shelving 9 to the rear of the 65 shelving. This partition 17 is spaced from the shelving 9 to form an entrance passageway 18 and the isles 11, 12 and 13 are divided by centrally located low partitions 19, 20 and 21 which extend from the partition 17 nearly to the closed end of said 70 isles but leaving space for passage around the ends of said partitions. The entrance to the passageway 18 is guarded by the turnstile 22 and the partition 17, has entrance 75 passageways opposite the respective isles 11, 12 and 13 which are guarded by the respective turn-stiles 23, 24 and 25, thus permitting access directly into either isle desired 80 from the passageway 18.

The shelving rows have doors 26 at convenient intervals to permit merchandise to be placed on the shelving from the rear. The customer passes in from the vestibule through the ante-room and along the passageway 18 to the desired turn-stile and there enters the isle desired and after entering must then follow the course of the shelving by the checking counter 7 to the exit. At the 85 checking counter 7, the goods selected are 90 checked and paid for.

The rear of the shelving is provided with suitable wire mesh 27 to retain the articles of merchandise in place and the doors 26 and partitions 17, 19, 20 and 21 may also be 95 formed of meshwork if desired.

It is to be noted that each succeeding tier of shelving from the front is longer than the one just in front of it, thus enabling those entering the store to see the ends of the various tiers of shelving and on the front end at a suitable place an index may be provided to indicate to the customer where the class of merchandise he wishes to buy may be found, thus saving the 100 purchaser the trouble of having to search through the entire list of articles in the store to find what he wishes to purchase.

What I claim is:

1. In a self-serving store, the combination with an inclosure of an entrance passageway formed of a row of shelving and a 110

partition spaced apart, said row of shelving being continuous around the partition and following a general zigzag course so as to produce a number of parallel aisles opening 5 toward the partition, each tier of said zigzag shelving being longer than the one just in front of it.

2. In a self serving store, in combination with an inclosure of an entrance passageway 10 formed of a row of shelving and a partition spaced apart, said row of shelving continuing on around the partition and following a general zigzag course so as to produce a

number of parallel aisles opening toward the partition, each tier of said zigzag shelving being longer than the one just in front of it and lattice work doors for forming a back to said shelving and turn-stiles in the partition opposite the respective aisles. 15

In testimony whereof I have signed my 20 name to this specification in the presence of two subscribing witnesses.

HOARD LEE.
